J. I. VINZANT

PLASTERER'S HAND GUARD

Filed August 24, 1925

Inventor:
Joseph I. Vinzant
by Hazard and Miller
Attorneys.

UNITED STATES PATENT OFFICE.

JOSEPH I. VINZANT, OF INGLEWOOD, CALIFORNIA, ASSIGNOR OF ONE-HALF TO RAYMOND MUSE, OF INGLEWOOD, CALIFORNIA.

PLASTERER'S HAND GUARD.

Application filed August 24, 1925. Serial No. 52,090.

To all whom it may concern:

Be it known that I, JOSEPH I. VINZANT, a citizen of the United States, residing at Inglewood, in the county of Los Angeles and State of California, have invented new and useful Improvements in Plasterers' Hand Guards, of which the following is a specification.

My invention is a plasterer's hand guard adapted to be attached to a trowel to protect the plasterer's hands from the injurious effects of cement and lime, particularly when used in placing a cement stucco. My hand guard is also applicable to a mason's trowel if so desired.

An object of my invention is to provide a simple covering which may be readily attached and detached from a trowel and form an effective covering to protect the hand which is particularly necessary when applying cement mortar as the cement is much more injurious to the plasterer's hands than is a lime mortar. At present most plasterers utilize cotton gloves which in ordinary work will only last for one day and moreover frequently become saturated with the water from the cement mortar injuring the hands through the glove.

My hand guard is preferably made of molded rubber adapted to fit over the handle of a plasterer's trowel, leaving sufficient space to readily grasp the handle and with the covering forming a guard coming well up over the back of the hand to the wrist. I also provide the guard with an opening at the back to provide sufficient ventilation to keep the hand cool. The molded rubber is provided with an aperture in the lower front end, which may be stretched to pass over the handle and engage the iron stem connected to the trowel and the rear end of the device is either connected directly to the end of the handle by a clamp bolt or by having a wire loop forming the connecting member to hold the base spread along the trowel.

My invention will be more readily understood from the following description and drawings, in which:

Figure 1 is a perspective view of my hand guard attached to a plasterer's trowel, showing what I may designate as the shoe-shaped guard.

Fig. 2 is a longitudinal section of the hand guard of Fig. 1.

Fig. 3 is a transverse section on the line 35 3—3 of Fig. 2.

Fig. 4 is a perspective view of a modified type of hand guard showing a more complete covering than the structure of Fig. 1 and with a freer opening at the rear for 60 ventilation.

Fig. 5 is a longitudinal section of the guard of Fig. 4.

Fig. 6 is a modification of the guard of Figs. 4 and 5 showing the rubber fabric of 65 the base engaging the rear end of the handle instead of the wire loop.

In the drawings, the trowel illustrated is of the type known as a plasterer's trowel having the usual flat blade 1, a central reinforcing bar 2, a stem 3 extending upwardly therefrom and a wooden handle 4 connected to the stem 3. The trowel may be of any ordinary type.

The hand guard shown in Figs. 1 to 3 of the shoe-shaped type is preferably formed of a molded rubber fabric somewhat in the form of a shoe, as indicated by numeral 5, having a base section 6, a toe section 7, a heel-strap 8, side sections 9 and an upper rim 10 through which the hand may be inserted. In this form a rather large opening 11 is preferably left at the heel, having a rim 12 adjoining the heel-strap, the sides and the base. This is for purposes of ventilation. An aperture 13 preferably having a reinforcing ring 14 also of rubber is formed in the base section somewhat near the toe portion of the guard.

This type of guard is inserted on the handle substantially as follows:—The aperture 13 is enlarged by stretching the ring 14 and the adjacent rubber fabric so that it may pass over the rear end 15 of the handle 4 and downwardly on the stem 3. The heel section is also formed with an aperture 16 also preferably having a reinforcing rim 17 through which is inserted a bolt 18 with a screw threaded end on which is fastened a nut 19 preferably with a washer 20 bearing on the rubber of the heel strap. In some types of trowels the horizontal portion of the stem passes through the handle and has a nut on the rear end which may be utilized, if not a bolt may be fitted or screwed into the rear end of the handle. Any other suitable type of fastening to secure the heel strap in place would be suitable.

In the construction of Figs. 4 and 5, the various details above described are somewhat similar, particularly in regard to the type of aperture 13, however the horizontal type of heel strap is discarded. The base of the hand guard at its rear end is provided with a loop 21 by turning a strap end 22 back on itself and securing it to the fabric at the base. A wire strap 23 extends from the 10 loop 21 and is attached to the rear of the handle by means of a bolt and nut similar to those used in connection with Figs. 1 to 3. In detail this strap is shown as being formed by a short piece of wire bent into 15 a flat ring 24, threaded through the loop 21, a straight section 25 and an eye 26 engaged by the bolt and nut.

It is believed that the manner of securing the guard of Figs. 4 and 5 to a trowel handle 20 is obvious, the aperture 13 being stretched and fitted over the handle and stem in the same manner as described in connection with Figs. 1 to 3. The wire strap 23 is connected over the end of the bolt and the end of the 25 handle as above described. In this form of hand guard the top portion 27 can be extended rearwardly further on the handle than in the construction of Figs. 1 to 3 and the rim 28 forming the edge for the top, 30 sides and base of the guard may be made to form a fairly tight fit around the wrist. This type of guard is particularly suitable for applying stucco plaster to outside walls as the hands are better protected from the 35 falling plaster and from the slopping of any cement water.

In the construction of Fig. 6, the same type of guard is used as shown in Figs. 4 and 5 except that a strap 29 formed integral 40 with the base section and being an extension thereof is turned up to engage the bolt and nut, having an aperture therethrough the same as the heel strap 8 of Figs. 1 to 3. This strap may likewise be designated as a heel 45 strap as it is positioned at the heel end of the hand guard.

My invention may be considerably modified in general construction and in specific features to suit different types of trowels 50 such as a mason's trowel or other types of plasterers' trowels. The type of hand guard may also be considerably modified in detail without departing from the spirit of my invention, for instance, if desired the guard could be made of non-resilient material and have the aperture such as 13 closed by a flap or the like which would button over and secure the two parts together, forming a fairly tight closure sufficient to prevent water entering around the stem.

Many other changes in detail will be apparent.

It will be noted in reference to Figs. 4, 65 5 and 6 that the wire strap 23 and the in-

tegral strap 29 have substantially the same function. The wire strap however, allows a freer opening for ventilation. Moreover, in some types of work where it is necessary to have freer ventilation to cool the hand 70 the top portion 27 may be considerably cut away.

Having described my invention, what I claim is:

1. A plasterer's hand guard comprising in 75 combination a trowel having a stem and a handle, the hand guard formed of flexible material having an aperture through the base adapted to fit over the stem and means to secure the rear end of the hand guard to the rear end of the handle, the guard extending partly over the said handle.

2. A plasterer's hand guard comprising in combination a trowel having a stem and a handle, a hand guard formed of flexible material having an aperture therethrough in the base, resilient material adjacent the aperture, the hand guard having a base section adapted to extend along the trowel, side sections to extend up the sides of the handle, a top section to extend over the top of the handle and means to secure the rear end of the hand guard to the rear end of the handle.

3. A plasterer's hand guard composed of 95 flexible material shaped to fit over a person's hand when holding a trowel and having an aperture through the lower surface, flexible material adjacent the aperture to allow the guard to be slipped over the handle and stem of a trowel and means on the rear end of the hand guard to attach to the rear end of the trowel handle.

4. A plasterer's hand guard as claimed in 100 claim 3, having in addition an opening formed near the rear end of the handle to allow ventilation.

5. A plasterer's hand guard formed of 105 flexible material shaped to fit over a hand in grasping a trowel handle, said guard having an aperture through the lower surface, flexible material adjacent the aperture to allow stretching to pass over a handle and engage the stem of a trowel, a heel strap at the rear end of the guard adapted to engage 110 the rear end of the handle of a trowel.

6. A plasterer's hand guard as claimed in 115 claim 5, in which the heel strap is in the form of a wire having a loop attached to the guard and an eye secured to the rear end of the handle of the trowel.

7. A plasterer's hand guard as claimed in 120 claim 5, in which the strap is in the form of a wire, the wire having a flat ring at the lower end and the hand guard having a rearward extension with a loop formed therein, the ring of the strap and the loop of the 125 guard interlocking, the handle having a bolt engaging an eye of the strap.

8. A plasterer's hand guard formed of flex-

ible material shaped to fit over a hand in grasping a trowel handle, said guard having an aperture through the lower surface, flexible material adjacent the aperture to allow stretching to pass over a handle and engage the stem of a trowel, a flexible means attached to the rear end of the guard and

connected to the rear end of the handle, said means being adapted to pivot on the end of the handle transversely and to allow front 10 and back movement of the hand guard.

In testimony whereof I have signed my name to this specification.

JOSEPH I. VINZANT.
